UNITED STATES PATENT OFFICE

CHARLES AUGUSTINE MULLEN, OF MONTREAL, QUEBEC, CANADA

APPARATUS FOR MANUFACTURING PAVEMENT

Original application filed June 18, 1928, Serial No. 116,996. Divided and this application filed December 5, 1927. Serial No. 237,901.

This invention relates to improvements in apparatus for manufacturing pavement, and in general, my invention relates to that type of pavement which is constructed of one, two, 5 or more layers of mixtures, which mixtures consist of intermingled, irregularly shaped rigid mineral or other particles, such as crushed stone, gravel, slag, sand, dust, known as the aggregate, coated and cemented together by bituminous plastic material, such as asphalt, tar, oil, known as the cementing medium, in which type of pavement such a layer or layers of mixtures is spread and compacted, while still sufficiently plastic, upon a 10 foundation or base or upon another such layer of mixture which previously has been spread, or spread and compacted.

In particular, my invention relates to a novel means and way of compacting the type 20 of pavement described in the foregoing paragraph, and specially to a novel means and way of compacting that type of pavement which is constructed of two or more layers of mixtures, each of which mixtures consists of intermingled irregularly shaped rigid mineral or other particles, which particles, known as the mineral aggregate, are graded from some maximum size down to a very small size so that when intermingled and 25 coated and cemented together by a bituminous cementing medium, spread and compressed, they produce a dense structure, in which type of pavement such a layer of mixture, the mineral aggregate of which is graded from about one-tenth to one-quarter 30 inch size down, is spread and compressed, while sufficiently plastic, upon another such layer of mixture, the mineral aggregate of which is graded from about three-quarters to one and one-half inch size down, which previously has been spread, or spread and compressed; and to the pavement resulting from 35 this novel way of compacting, which is itself novel in that it has characteristics resulting from this novel method of compacting, such as greater uniformity of density and compaction.

Heretofore, the compacting of this type of pavement has been accomplished, in the 40 earliest years of the industry, by gang tamp-

ing which consisted of a number of laborers lifting and dropping heavy tamping irons on the mixtures after they have been distributed to place; and, later, by both hand and self-propelled rollers. Each of these 55 methods has its faults, most of which my invention eliminates.

Hand tamping was superior to rolling because the vertically delivered blow compacts bituminous paving mixtures better than 60 slowly applied pressure from a roller, which has a tendency to shove the material ahead rather than to drive it vertically down into place, but hand tamping required much labor, and the difficulty in maintaining a gang 65 of workmen to so high a point of efficiency that it would be properly done was almost insurmountable. Tamping is also superior because, as the face of the tamper is short, it operates on an area so restricted that there 70 is the minimum of opportunity for bridging sections where the mixture has not been spread sufficiently heavy.

Hand rolling is impractical for securing 75 compaction for the reason that it is not possible to operate a sufficiently heavy roller for that purpose by hand power; yet, it is free from one of the principal objections to self-propelled rollers operated by steam or otherwise, in that power, being applied by men at 80 the end of a long handle, the thrust of propulsion is not in the roller itself, and therefore the tendency to shove the mixture ahead of a hand roller is not nearly so great.

The purpose of my invention is to secure a 85 method of compacting bituminous paving mixtures into pavements such as I have described which will be, as far as possible, free from the objections to the methods previously in use; and to this end I have applied mechanical power tamping through an apparatus, tamper or roller, which is preferably not self-propelled by means of the surface delivering the blows. Compressed air has so far been used as the mechanical 90 power; but obviously steam, electricity, or any other source of artificial power will produce at least approximately the same result.

A further purpose of my invention is to 95 permit the economical laying of such asphalt 100

paving mixtures as I have described in relatively small areas in buildings, on tennis courts, and in all restricted places where only the mastic asphalt method is now regularly used, which produces a pavement or flooring with undesirable characteristics resulting from said mastic method of floating the mixtures into place.

This has heretofore been impossible because of the high cost of the tamping gang and the difficulty of getting a steam roller into such places as small cellars and buildings and the difficulty with which such rollers are moved from place to place, which is too expensive for small area work.

My invention consists in a method of compacting a pavement, in one or more layers, and in the pavement resulting from the application of that method, and the apparatus therefor, by which method I secure a pavement more uniformly and more satisfactorily compacted than heretofore possible, by employing in combination the distributing into place of bituminous paving mixtures and operating thereupon while they are still sufficiently plastic a power driven tamping plate or roller of such size as to give the desired degree of compaction without having a sufficient length of plate or roller bearing upon the mixture to span sections where the distribution is not sufficiently heavy.

A further feature of my invention consists in applying this method to a two or more layer pavement such as patented to me by the Canadian Patent Office under Letters Patent Number 247,652, issued March 17, 1925, in which the plate or roller transmitting the tamping blows to the asphalt paving mixture used for an under layer bears a pattern as set forth in aforesaid Letters Patent; and, where, if it is desired to use the same method for compacting the top or surface layer, then in order to produce a non-slippery, non-skid surface, the plate or roller may bear a pattern for producing a uniformly marked surface, or, if a perfectly smooth surface is desired, then the surface of the plate or roller may be smooth.

My improved method may be carried out and my improved pavement constructed by the preferred apparatus hereinafter described in detail.

In the drawings, in which like characters of reference indicate corresponding parts in all figures:

Figure 1 is an elevation of one embodiment of apparatus which may be used to carry out my invention and which, as apparatus itself, contains certain features of the invention;

Figure 2 is an elevation of an alternative form of roller which may be used;

Figure 3 is an end elevation of the apparatus shown in Figure 1;

Figure 4 is a side view of another alternative form of roller;

Figure 5 is a sectional detail taken through the oil or lubricating box.

In the drawings, A indicates a tamping member shown in the form of a heavy metallic roller designed to be moved over the surface of the material to be tamped and while being moved to be subjected to power blows. The form of roller illustrated is formed with corrugations 10 designed to impress a predetermined pattern on the surface being tamped. The roller carries an axle 12 on which the tamping means B are mounted by means of a frame C. The frame C is conveniently in the form of an arch having end extensions 13 and 14 with journals 15 and 16 mounted on the ends of the axle 12. The central part 17 of the arch constitutes an anvil or shock-distributing member to receive the blows of the plunger 18 of the power tamping device B. This power tamping device B may be conveniently in the form of an air gun, the construction of which is known in the art and which, when supplied with a source of compressed air as from the pipe 19, is designed to cause the member 18 to deliver a plurality of power blows on the member 17 which are thereby transmitted through the axle 12 to the tamping member A.

Means may be provided for absorbing the shock of the air gun, such means comprising supporting arms 20 and 21 leading from the outer extremity of the frame C and extending through a cross bar 22 connected to the member B, springs 23 extending from nuts 24 on the arms 20 and 21 to the upper side of the cross bar, whereby the upward movement of the power gun will be resisted by the said spring.

Means are conveniently provided for manually or otherwise propelling the tamping member. The means that I have illustrated comprise handles D extending on opposite sides of the member C by means of which the tamping member may be moved.

E indicates a box or container designed to contain lubricating material such as oil-saturated waste which will clean the surface of the roller A, and having sides 25 and 26 which act as a scraper on the roller.

The form of the roller A' shown in Figure 2 differs only in the form of pattern from the roller shown in Figure 1. Another varied form of pattern is shown in Figure 4, where the roller A² is formed with spiral grooves.

It will be observed that the oil waste in the box E in addition to wiping the roller will serve to spread a thin film on it as it turns over to thereby prevent adhesion of the plastic asphalt pavement mixture to the roller.

The practice of the invention will be apparent from the foregoing specification. When the paving mixture has been laid, the

- tamping roller is moved over it and simultaneously the air gun B is operated to deliver a rapid succession of power blows which are transmitted through the roller A which thereby serves as a compacting member to produce in the paving mixture a density substantially greater than could be produced by hand tamping. This also gives uniformity and stability to the pavement.
- 5 10 It will be observed that the compacting roller A is comparatively short and has an insufficient bearing to span sections in the spread paving mixture where the distribution of the mixture is insufficiently heavy. The bearing surface is also relatively narrow and thus adapted to produce uniformity in compression.
- 15 As many changes could be made in the above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.
- 20 What I claim as my invention is:
1. A compacting tool of the character described, comprising a portable compacting roller, a frame mounted on the roller, an anvil member formed on the frame and a power tamping device adapted to register with and deliver blows against the anvil member supported on the frame, opposed handle means connected with the frame for moving the roller over the material to be tamped and a scraper member connected with the frame and adapted to contact with the roller.
- 25 2. A compacting tool of the character described, comprising a portable compacting roller, a frame mounted on the roller, an anvil member formed on the frame and a power tamping device adapted to register with and deliver blows against the anvil member resiliently supported on the frame, means connected with the frame for moving the roller over the material to be tamped and means for moistening the surface of the roller to eliminate adherence of the treated substance.
- 30 3. A compacting tool of the character described comprising a portable compacting roller, a frame mounted on the roller, an anvil member formed on the frame and a power tamping device adapted to register with and deliver blows against the anvil member resiliently supported on the frame, means connected with the frame for moving the roller over the material to be tamped, a scraper member connected to the frame and adapted to contact with the roller, and means for moistening the surface of the roller to eliminate adherence of the treated substance.
- 35 4. A compacting tool of the character described comprising a portable compacting roller formed with uniform pattern making depressions therein, a frame mounted on the roller, an anvil member formed on the frame and a power tamping device adapted to register with and deliver blows against the anvil member, means connected with the frame for moving the roller over the material to be tamped, and
- depressions therein, a frame mounted on the roller, an anvil member formed on the frame and a power tamping device adapted to register with and deliver blows against the anvil member resiliently supported on the frame, and opposed handle members connected with the frame for moving the roller over the material to be tamped.
5. A compacting tool of the character described comprising a portable compacting roller formed with uniform pattern making depressions therein, a frame mounted on the roller, an anvil member formed on the frame and a power tamping device adapted to register with and deliver blows against the anvil member resiliently supported on the frame, means connected with the frame for moving the roller over the material to be tamped, a scraper member connected to the frame adapted to contact with the roller and cooperate with the depressions therein, and lubricating means for the roller.
6. A compacting tool of the character described comprising a portable compacting roller formed with a series of uniform corrugations therein adapted to compact and form an even pattern in the treated substance, a frame mounted on the roller, an anvil member formed on the frame, a power tamping device resiliently supported on the frame adapted to register with and deliver blows against the anvil member, and means for lubricating the surface of the roller.
7. A compacting tool of the character described comprising a portable compacting roller formed with uniform pattern making depressions therein, a frame mounted on the roller, an anvil member formed on the frame, an air gun resiliently supported on the frame adapted to register with and deliver blows against the anvil member, opposed handle members secured to the frame for moving the roller over the material to be tamped, whereby said material is simultaneously rolled, tamped and formed with a uniform pattern.
8. A compacting tool of the character described comprising a portable compacting roller, a frame mounted on the roller, an anvil member formed on the frame, a power tamping device adapted to register with and deliver blows against the anvil member supported on the frame, means connected to the frame for moving the roller over the material to be tamped, and a casing member secured to the frame adapted to encase lubricating means for the roller.
9. A compacting tool of the character described comprising a portable compacting roller formed with uniform pattern making depressions therein, an anvil member formed on the frame, a power tamping device supported on the frame adapted to register with and deliver blows against the anvil member, means connected with the frame for moving the roller over the material to be tamped, and

means for scraping and lubricating the roller including a casing secured to the frame adapted to conform to the contour of the roller and contact therewith and to encase lubricating saturated material.

10. A compacting tool of the character described comprising a portable compacting roller, a frame mounted on the roller, an anvil member formed on the frame, power tamping device resiliently supported on the frame adapted to register with and deliver blows against the anvil member, means connected with the frame for moving the roller over the material to be tamped, and means for scraping and lubricating the roller including a casing in connection with the frame adapted to contact with the roller and encase lubricating saturated material.

15. In witness whereof I have hereunto set my hand.

CHARLES AUGUSTINE MULLEN.
